COMBINED SINK DIVIDER MAT AND SOAP HOLDER

Charles O. Bliss, Los Angeles, Calif.

Application September 18, 1958, Serial No. 52,681

Term of patent 14 years

(Cl. D9—6)

FIG. 1

FIG. 3

Fig. 1 is a top plan view of a combined sink divider mat and soap holder showing my new design;

Fig. 2 is a side view thereof; and

Fig. 3 is a sectional view on a larger scale on the line 3—3 of Fig. 2.

Both sides of the mat have the same appearance.

I claim:

The ornamental design for a combined sink divider mat and soap holder, substantially as shown and described.
